[57] CLAIM

The ornamental design for an aero deflector for vehicles, as shown and described.

DESCRIPTION

FIG. 1 is a rear side perspective view of an aero deflector for vehicles showing my new design mounted on a vehicle, wherein a fragment of the vehicle is shown in broken lines for illustrative purposes only and forms no part of the claimed aero deflector design;

FIG. 2 is a top front perspective view of the aero deflector of FIG. 1;

FIG. 3 is an enlarged rear view of the aero deflector of FIG. 1;

FIG. 4 is a top view of FIG. 3;

FIG. 5 is a left side view of FIG. 3;

FIG. 6 is a right side view of FIG. 3;

FIG. 7 is a front view of FIG. 3; and,

FIG. 8 is a bottom view of FIG. 3.
